CLAIM

The ornamental design for a portable power conversion plug, as shown and described.

DESCRIPTION

FIG. 1 is a first perspective view of a portable power conversion plug showing my new design;

FIG. 2 is a second perspective view thereof;

FIG. 3 is a third perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof.

FIG. 10 is an exploded view thereof; and,

FIG. 11 is a further exploded view thereof.

The broken lines in the figures depict portions of the portable power conversion plug that form no part of the claimed design.

1 Claim, 11 Drawing Sheets
